UNITED STATES PATENT OFFICE.

CHARLES M. LANE, OF ROSEDALE, KANSAS.

BORING MACHINE.

1,114,373.

Specification of Letters Patent.

Patented Oct. 20, 1914.

Application filed December 4, 1913. Serial No. 804,737.

To all whom it may concern:

Be it known that I, CHARLES M. LANE, citizen of the United States, residing at Rosedale, in the county of Wyandotte and State of Kansas, have invented certain new and useful Improvements in Boring-Machines, of which the following is a specification.

My invention relates to new and useful improvements in wood boring tools, the object of my invention being to provide a portable boring tool or machine which may be readily employed in restricted spaces, such as in boring holes through the sills of freight cars or through a series of rafters where an ordinary bit and brace could not be employed.

A further object of my invention is to provide a bit carrying member and bit driving means so arranged in a common frame that the bit may be driven from a shaft extending at an angle to the bit.

A further object of my invention is to provide a guide upon which this frame may be mounted to insure the boring of straight holes.

With these and other objects in view, my invention will be more fully described, illustrated in the accompanying drawing, and then specifically pointed out in the claims which are attached to and form a part of this application.

In the drawing Figure 1 is a perspective view of my improved boring machine in use; Fig. 2 is a vertical sectional view taken through the longitudinal axis of the bit receiving sleeve of the machine; Fig. 3 is a fragmentary top plan view, bringing out more clearly the manner in which the bit carrying frame is mounted upon the guide; Fig. 4 is a sectional view on the line 4-4 of Fig. 2.

Corresponding and like parts are referred to in the following description and indicated in all the views of the drawing by the same reference characters.

The preferred embodiment of my invention consists primarily of a bit carrying frame, indicated as a whole by the numeral 10 and a guide member 11. The bit carrying frame is substantially rectangular in shape, being formed from strip metal and in two parts. The main portion of the frame is formed from a single piece of strip metal bent into U-shaped configuration to provide a top 12 and spaced sides 13 and 14.

The free or lower ends of these sides are connected by a second strip of metal, the ends of which are upbent to rest between the ends of the first strip as shown at 15, being secured in place by rivets or other suitable fastening devices 16 and the intermediate portion of which extends in parallel relation to the intermediate portion 12 of the main member of the frame. The intermediate portions of the sides 13 and 14 of this frame 10 are braced and held in proper spaced relation by a cross member 17 which extends between the side members and the ends of which are bent downwardly and riveted thereto as shown at 18. The members 15 and 17 are provided with alined bores 19 to rotatably receive a drive shaft 20 carrying at its inner end a miter gear 21, this miter gear resting against the member 17 and consequently holding the shaft against outward movement from the frame.

The side portions 13 and 14 of the frame, immediately above the miter gear 21, are provided with alined openings 22 to rotatably receive a sleeve 23, the ends of which project slightly beyond the side members of the frame. A miter gear 24 is pinned or otherwise secured upon this sleeve, meshing with the miter gear 21 and bearing against the inner face of the side portion 14 of the frame 10. The engagement of the gears 21 and 24 holds the shaft 20 against inward movement and the sleeve 23 against movement toward the side member 13 of the frame, while the engagement of the gear 24 against the side member 14 of the frame holds the sleeve 23 against movement in the opposite direction.

A universal joint 25 connects the free end 95 of the shaft 20 with one end of a shaft 26, the opposite end of which terminates in a head 27 having angularly disposed faces for locking engagement in the chuck 28 of a conventional form of bit brace 29. It will 100 of course be clear that manipulation of the bit brace in the usual manner will act through the shafts 26 and 20 to rotate the sleeve 23. If desired, a flexible drive shaft, leading from any suitable source of power 105 and terminating in a chuck corresponding to the chuck 28, may be employed in place of the brace 29 in order to avoid the necessity of manually operating the machine.

The sleeve 23 is adapted to receive the 110 shank 30 of a bit 31, this bit being held against movement in the sleeve by a set

screw 32. As the strain tending to turn the bit shank in this sleeve is considerable, the bit shank and bore of the sleeve are preferably elliptical or otherwise non-circular in cross section although practically the same result may be reached by merely making the shank of the bit elliptical with its major axis equal to the diameter of the sleeve and in threading the set screw against 10 one of the faces of least curvature of the shank.

It will of course be apparent that the above described machine will occupy but little space in use as the frame itself need 15 only be one or two inches wide and the bit shank need be no longer than the width of the frame. The space required for proper manipulation of the machine is therefore but little greater than the length of the 20 effective portion of the bit employed.

In order to provide means for supporting the tool or machine when in use and also for guiding the bit during its passage through the wood or other substance being bored, I provide the frame 10, at one side, 25 with a hanger or bracket, indicated as a whole by the numeral 33. This bracket consists of an L-shaped strip of metal 34, one arm of which rests upon and is secured to 30 the intermediate portion 12 of the frame by a bolt 35 and nut 36 and the other arm of which extends in parallel and slightly spaced relation to the frame 10. A second strip of metal 37 is secured by its ends to 35 the outer face of the intermediate portion of the strip 34 with its intermediate portion spaced from the strip to provide a guide loop 38.

A guide, previously indicated by the 40 numeral 11, co-acts with this bracket or handle to support and direct the machine and its bit. This guide is formed from a single piece of strip metal having its end portions bent at right angles to the body portion to 45 provide spaced arms 39 and 40. The former of these arms is reduced somewhat in width at its free end as shown at 41 to permit ready passage of said arm into and through the loop 38 of the hanger, while the free end 50 of the arm 40 is bifurcated and spread to provide diverging feet 42. Both arms are of the same length and the terminal 41 of one and the feet 42 of the other serve as a three-point support for the guide to, at all 55 times, maintain its arm 39 at right angles to the surface of the work upon which the machine is employed.

In use, the machine proper is mounted upon the guide and employed in the manner shown in the drawing. The guide may be 60 manually held in place or may be secured in place by means of wedges 43, if deemed expedient. During the boring operation, the bit is fed by moving the frame 10 along the arm 39 of the guide and as this arm is, at 65 all times, at right angles to the work being operated upon, the boring of straight holes is insured.

Although I have illustrated the boring machine in all its details, it will of course be 70 understood that I do not wish to be limited to the specific features of construction illustrated and described, as various minor changes, within the scope of the appended claims, may be made at any time desired, 75 without in the slightest degree departing from the spirit of my invention.

Having thus described the invention, what is claimed as new is:

1. A boring machine including a boring 80 mechanism carrying frame, a hanger bracket carried by the frame and provided with a guide loop, and a guide having parallel spaced arms, one of which is mounted for sliding movement through the loop of the 85 hanger bracket.

2. A boring machine including a boring mechanism carrying frame having parallel spaced side members, the free end of one side member being bifurcated and spread to provide diverging feet, a frame, and a hanger bracket carried by the frame and provided with a guide loop to receive the other side 90 of the guide member.

3. A boring machine including a U-shaped 95 frame formed from a single strip of metal, braces across the open end and intermediate portions of the frame and connecting the side members, the braces also being formed of strip metal, a sleeve journaled in the side 100 members of the frame between one brace and the closed end of the frame, a shaft journaled in the braces, meshing beveled gears carried by the shaft and sleeve and locking both the shaft and sleeve against longitudinal movements in their bearings, a guide loop carried by the frame, and means engageable in the guide loop for supporting the frame.

In testimony whereof I affix my signature in presence of two witnesses.

CHARLES M. LANE. [L. S.]
